UNITED STATES PATENT OFFICE

RUDOLF DAMEK, OF ORANGE, NEW JERSEY

ANKLET

Application filed October 23, 1930. Serial No. 490,759.

An object of the invention is to provide an anklet which may be worn around the ankle to assist in retaining the heat of the body, it being possible to decorate the anklet as 5 may be desired.

Another object of the invention is to provide an anklet of a form and secured by a means which will permit the tendons at the ankle to have free play, so that the anklet may 10 be worn without inconvenience when walking or dancing and without danger of the anklet working out of place by the movement of the tendons.

Additional objects of the invention will appear in the following specification in which the preferred form of the invention is described.

In the drawings similar reference characters refer to similar parts in both views, of 20 which

Figure 1 is a view illustrating the manner in which the anklet is worn, and

Figure 2 is a view illustrating the anklet in extended form.

25 On referring to the drawings it will be seen that the anklet 9, which is the subject matter of this application, may be provided with fur 10 at its lower edge and may be decorated as may be desired, the anklet being constructed to open at the front of the ankle and the edges 11 of the anklet being disposed in the manner illustrated in Figure 1.

30 Any suitable means may be employed to secure together the ends of the anklet adjacent their lower edges. In the drawings fastening means 12 and 13 are provided, but any other suitable fastening means may be employed.

35 The body 9 of the anklet will be disposed at the back and the sides of the ankle of the wearer. The ends 11 of the anklet, as the anklet will be worn, will be disposed at the front of the ankle, as shown in Figure 1 of the drawings, and these ends from their lower edges will diverge upwardly, so that while the ends of the anklet will be secured together adjacent their lower edges, the upper portions of the anklet at their ends 11 will not bind at the tendons, which would cause inconvenience 40 in walking or dancing. Furthermore, the

ends 11 of the anklet above their lower edges will not only be free from each other, but will be spaced from each other so that there may be a free movement of the tendons at the front of the ankle and this movement will not serve to move the anklet out of position. 55

What is claimed is:

An anklet having a flexible member with a bottom provided with front meeting ends at the bottom, the rear of the flexible member extending substantially vertically from its bottom, the sides of the top of the flexible member extending forwardly substantially parallel with the bottom for a distance and then converging downwardly to the front 60 meeting ends at the said bottom, and means to secure the front meeting ends at the bottom together the front meeting ends being free from each other above the said means. 65
